CLAIM

The ornamental design for a mouse jiggler, as shown and described.

DESCRIPTION

FIG. 1 is a top, front, right perspective view of my design for a mouse jiggler with the top removed in an open configuration;

FIG. 2 is bottom, front, right perspective view thereof;

FIG. 3 is a top, front, right perspective view of the mouse jiggler in a closed configuration;

FIG. 4 is a bottom, front, right perspective view thereof;

FIG. 5 is a front elevational view of the top cover of the mouse jiggler, the rear elevational view is identical;

FIG. 6 is a left side elevation view thereof, the right side elevation view being identical thereof;

FIG. 7 is a top plan view thereof;

FIG. 8 is a bottom plan view thereof;

FIG. 9 is a front elevation view of the bottom portion of the mouse jiggler; and

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines in the figures depict portions of the mouse jiggler, that form no part of the claimed design.
